UNITED STATES PATENT OFFICE.

SAMUEL G. WILKES, OF TAUNTON, MASSACHUSETTS, ASSIGNOR TO REED AND BARTON CORPORATION, A CORPORATION OF MASSACHUSETTS.

DESIGN FOR A CHAFING-DISH, LAMP, AND STAND.

No. 38,924.

Specification for Design.

Patented Dec. 3, 1907.

Application filed January 14, 1907. Serial No. 352,311. Term of patent 14 years.

To all whom it may concern:

Be it known that I, SAMUEL G. WILKES, a citizen of the United States, residing at Taunton, in the State of Massachusetts, have invented a new, original, and ornamental Design for a Chafing-Dish, Lamp, and Stand, of which the following is a specification, reference being had to the accompanying drawing, forming a part thereof.

The figure is a view in elevation showing

my new design as applied to a chafing dish, lamp and stand.

I claim

The ornamental design for a chafing dish, lamp and stand as shown.

SAMUEL G. WILKES.

In presence of—

GEORGE E. CHAMBERS,
HERBERT O. WOOLLEY.
